(57) **CLAIM**

The ornamental design for a protection case for an electronic tracking device, as shown and described.

DESCRIPTION

FIG. 1 is a perspective view including the front, top, and side of a protection case for an electronic tracking device;

FIG. 2 is a perspective view including the rear, bottom, and opposite side of the protection case for an electronic tracking device of FIG. 1;

FIG. 3 is a front elevation view of the protection case for an electronic tracking device of FIG. 1;

FIG. 4 is a rear elevation view of the protection case for an electronic tracking device of FIG. 1;

FIG. 5 is an opposite side elevation view of the protection case for an electronic tracking device of FIG. 1;

FIG. 6 is a side elevation view of the protection case for an electronic tracking device of FIG. 1;

FIG. 7 is a top plan view of the protection case for an electronic tracking device of FIG. 1;

FIG. 8 is a bottom plan view of the protection case for an electronic tracking device of FIG. 1;

FIG. 9 is a perspective view including the front, top, and side of a protection case for an electronic tracking device shown in a configuration of use;

FIG. 10 is a perspective view including the rear, bottom, and opposite side of the protection case for an electronic tracking device of FIG. 9;

FIG. 11 is a front elevation view of the protection case for an electronic tracking device of FIG. 9;

FIG. 12 is a rear elevation view of the protection case for an electronic tracking device of FIG. 9;

FIG. 13 is an opposite side elevation view of the protection case for an electronic tracking device of FIG. 9;

FIG. 14 is a side elevation view of the protection case for an electronic tracking device of FIG. 9;

FIG. 15 is a top plan view of the protection case for an electronic tracking device of FIG. 9; and,

(Continued)

FIG. 16 is a bottom plan view of the protection case for an electronic tracking device of FIG. 9. The broken lines depict portions of the protection case for an electronic tracking device that form no part of the claimed design.
